UNITED STATES PATENT OFFICE

FREDERICK D. REYNOLDS, OF ST. LOUIS, MISSOURI

COMBINED UTILITY CABINET AND STAND

Application filed November 15, 1926. Serial No. 148,546.

This invention relates to a combined utility cabinet and stand.

The objects of my invention are to provide a collapsible cabinet comprising corner posts, a series of shelves supported therein and a hinged cover for the top shelf, said shelves being detachably secured to said posts whereby the device may be stored or shipped in knock-down condition in order to reduce the 10 cost of storage and shipping.

Other objects of the invention are to provide said shelves with center apertures so that the stand may be used as a Christmas tree stand, the basal end of the trunk of the tree 15 being inserted through said apertures.

Further objects of the invention are to form said apertures with annular flanges and provide said flanges with suitable means for securing the trunk in position therein.

Still further objects of the invention are to form the corner posts with suitable brackets having upwardly presented end portions spaced from said corner posts and to form 20 said shelves near the corner thereof with suitable openings for receiving said upwardly presented end portions of the brackets, thereby providing a rigid and secure interlock between the corner posts and said shelves.

With these and other objects in view, my 30 invention consists of certain novel features of construction and arrangement of parts, hereinafter more fully described and claimed in the accompanying drawings, in which—

Figure 1 is a top plan view of the stand. 35 Figure 2 is a side elevational view thereof showing the cover removed and the lower end of the Christmas tree in dotted lines extending through the openings in the shelves and secured in position therein.

Figure 3 is a vertical cross section through the stand showing the cover in raised position.

Figure 4 is a top plan view of the stand 45 with the cover removed.

Figure 5 is an enlarged fragmental view of one corner of the stand.

Figure 6 is a fragmental cross section taken on lines 6—6 of Figure 5.

Figure 7 is a cross sectional detail view of

the removable hinge connection of the cover. Figure 8 is an elevational view thereof.

Figure 9 is a fragmental sectional view of one of the shelves and showing a support removably arranged in the center opening 55 thereof.

Referring by numerals to the accompanying drawings, 10 indicates corner posts preferably formed of angle iron and having their lower ends bent outwardly to provide feet 11. 60 Each corner post is provided near its upper end with a bracket 12 having a portion 14 secured in any suitable manner to the corner post 10 and terminating in an upwardly presented end portion 15 which is spaced from the respective corner post and terminates slightly before the plane of the upper end of said corner post. The spacing of the end portion inwardly provides a horizontally disposed portion 16 which forms a support for 70 the top shelf 17. The latter is provided near each corner with an opening 18 through which end portion 15 projects upwardly. Shelf 17 is provided with an upwardly presented marginal flange 19, the corners of which bear 75 against the inner faces of corner posts 10 when said shelf is placed in position on the posts.

In order to provide a secure interlock between the shelf and the corner posts and eliminate play and rattling of the parts, flange 19 is formed in each corner portion with a horizontally and inwardly disposed protuberance 20 which, when said shelf is in position, engages one side of end portion 15 thereby providing a frictional interlock between the shelf and corner posts 10 and portions 15. In this manner the shelf and the corner posts are held together without the use of extraneous attaching means. The corner posts are maintained in proper position at all times and the parts are held against accidental disengagement from each other.

Shelf 18 is provided with a central opening 21 having a downwardly presented flange 22, the edge of which is rebent as indicated at 22^a in order to reinforce said edge and provide sufficient amount of metal for receiving screws 24 which latter are screwseated therein 100

and have their ends projecting into opening 21.

The purpose of opening 21 is to allow the insertion therethrough of the basal end of a Christmas tree or a flag pole or the like as indicated in dotted lines at A in Figure 2. When the stand is utilized as a support for a Christmas tree, a water container B is arranged on the floor so as to receive the end 10 of the trunk.

An intermediate shelf 25 is detachably secured in position a suitable distance below top shelf 17 by brackets 26 which latter are secured to corner posts 10 substantially half way between the feet 11 and upper ends of 15 said corner posts. The method of attachment is substantially the same as that of the upper shelf 17 with the exception that in the construction of shelf 25 the edge thereof is 20 turned downwardly to form a depending marginal flange 25^a which rests on the horizontal portion of brackets 26. Consequently it is not necessary to aperture said shelf 25. A central opening 27 is formed in said shelf 25 coaxially with opening 21 of shelf 17 and the edge of flange 28 forming opening 27 is rebent as indicated at 29 and a pair of screws 30 is screwseated in said flange substantially at 25 right angles to screws 24 for engaging member A. Shelf 25 serves to reinforce the stand and tie the corner posts 10 at points below shelf 17.

The main portion of shelf 17 is preferably depressed as indicated at 17^a so as to provide 30 suitable spaces for storing various articles. When the stand is used as a shoe-shining stand this depressed portion can contain shoe brushes and cans of shoe polish. A cover 31 is provided for enclosing the upper end of the 35 stand and provide a closure member for shelf 17. This cover which has depending marginal flanges 31^a is secured to hinge members 32 which are detachably secured by rebent portions 34 to the upwardly turned marginal flange 19 of shelf 17. Portions 34 are arranged 40 to frictionally hold the flanges in position and are adapted to be disengaged from marginal edge 19 so as to permit the removal of cover 31.

Shelf 17 is not sufficiently deep to accommodate a bottle of polish or other similar container and I therefore provide supporting means 35 which may be slipped into opening 21 and support a bottle in upright position as shown in Figure 9. This means consists 50 of a pair of U-shaped members 36 having their horizontally disposed uniting portions 37 pivotally connected together as indicated at 55 38 and having the extremities 40 of their parallel leg portions 39 bent outwardly at right angles so as to rest on the bottom of shelf 17 and support said means in said opening 21. When said supporting means are not in use 60 means 36 can be folded together on their pivot 38 when stored away for future use.

65 My utility stand may be also used as a bath

stool, in which case compartment 17^a can be utilized to hold soap and other articles.

My combined utility stand and cabinet has all of its parts formed of metal, thereby providing strong construction and occupying 70 very little space. The various parts are detachably secured together so that the stand can be taken apart.

While I have shown and described the preferred form of my invention, it is obvious 75 that various changes could be made in the construction and arrangement of parts of my device without departing from the spirit of my invention.

I claim:

1. A utility stand comprising corner posts, brackets secured at their lower ends to said posts and having their upper ends disposed vertically and spaced inwardly from the upper ends thereof, a top shelf provided with 80 an upwardly presented marginal flange and having its bottom provided near the corners thereof with openings disposed horizontally for receiving said vertically disposed spaced ends of said brackets, whereby said shelf is 90 detachably supported on said posts, and a closure member for said shelf and the upper ends of said corner posts, said shelf being provided with a central opening adapted to receive the basal end of a member to be supported by said stand. 95

2. A utility stand comprising in combination corner posts, brackets secured at their lower ends to said posts and having their upper ends disposed in vertical planes in 100 spaced parallel relation with the upper ends thereof, a top shelf provided with an upwardly presented marginal flange and having its corners with openings disposed horizontally for receiving the vertical spaced ends 105 of said brackets, whereby said shelf is detachably supported on said posts, a closure member for said shelf and the upper ends of said corner posts, said shelf being provided with a tubular depending extension 110 adapted to receive the basal end of a member to be supported by said stand, and means carried by said tubular extension for securing said member in position therein.

3. A utility stand comprising corner posts, 115 brackets secured to and spaced laterally from the upper ends thereof, a shelf extending between the upper ends of said corner posts and provided near its corners with openings for receiving said brackets, thereby interlocking said shelf with said corner posts, said shelf being provided with a central flanged opening, and screws threaded in the flange of said opening and extending thereinto for securing and supporting therein the basal end 120 of the article to be supported by said stand. 125

4. A combined utility stand and cabinet comprising corner posts having upwardly presented portions spaced inwardly from said corner posts, a top shelf having an upwardly 130

- presented marginal flange and provided in its bottom near the corners thereof with seats for receiving the upwardly presented portions disposed near the upper ends of said corner posts, an intermediate shelf removably engaging the portions disposed intermediate the ends of said corner posts for tying said corner posts together at points spaced intermediate the ends thereof, and a hinged cover detachably secured to the upward flange of said top shelf for enclosing the latter and the upper ends of said corner posts. 5. A combined utility stand and cabinet comprising corner posts having inwardly extending and upwardly presented portions, a top shelf having an upwardly presented marginal flange and provided in its corners with seats for receiving the upwardly presented portions disposed near the upper ends of said corner posts, an intermediate shelf removably engaging portions disposed intermediate the ends of said corner posts for tying said corner posts together at points spaced intermediate the ends thereof, a hinged cover detachably secured to the upward flange of said top shelf for enclosing the latter and the upper ends of said corner posts, said top shelf being recessed to provide a chamber for receiving various articles and being further provided with a centrally disposed seat for removably engaging an article to be supported thereby. 6. A utility stand comprising corner posts of angle irons the lower ends of said posts being flared outwardly to form feet, brackets secured to the upper ends of said posts and provided with upwardly presented portions spaced inwardly from said posts, a top shelf formed of sheet metal and having its edge presented upwardly to form a marginal flange, said shelf being provided near its corners with openings for receiving the upwardly presented portions of said brackets, protuberances formed in the corners of said marginal flanges and extending inwardly for frictionally engaging the upward projecting portions of said brackets so as to frictionally interlock said shelf with said corner posts, an intermediate shelf formed of sheet metal and engaging said corner posts at points spaced a suitable distance below said top shelf, and a cover having a downwardly presented marginal flange for removably engaging said top shelf and for a closure member therefor. 7. A knockdown utility stand comprising in combination corner posts having their lower ends flared outwardly to form feet, vertically disposed projections secured to the upper ends of said corner posts and spaced inwardly and laterally therefrom thereby forming horizontally disposed shoulders, a shelf provided in its bottom near its corners with seats adapted to interengage detachably
